United States Patent Office.

WILLIAM C. JOSLIN, OF WEST THOMPSON, CONNECTICUT.

Letters Patent No. 69,219, dated September 24, 1867.

IMPROVED MACHINE FOR REDUCING ROLLER LEATHER TO A UNIFORM THICKNESS.

The Schedule referred to in these Letters Patent and making part of the same.

KNOW ALL MEN BY THESE PRESENTS:

That I, W. C. JOSLIN, of West Thompson, in the county of Windham, and State of Connecticut, have invented certain new and useful improvements in Machines for Reducing Roller and other Leather to a Uniform Thickness; and I do hereby declare that the following is a full, clear, and exact description of the same, reference being had to the accompanying drawing, forming a part of this specification, in which—

Figure 1 represents a top or plan view of my improved machine, and

Figure 2 represents a section on line A B, fig. 1.

To enable those skilled in the art to which my invention belongs to make and use the same, I will proceed to describe it more in detail.

In the drawings, the part marked A represents the main frame, upon the top of which are supported, in suitable bearings, the receiving-rolls B B and the delivering-rolls C C, as fully indicated in the drawings. Between the receiving and delivering-rolls is supported the reducing-wheel or cylinder D, which, in this instance, is made with spiral knives *a a* upon its outer surface. The knives may be applied in spiral form, or they may be put on parallel to each other, and any desired number may be used. E E are two friction or supporting-rolls, to support the material during the operation. F is a bed to support the material under the reducing-wheel. The bed F is fitted to work up and down at each end in suitable grooves or recesses *b*, in the side of the frame. Bed F can be adjusted up or down by means of screws *c*, which pass through ear-pieces *d*, fastened to sides of frame A. Screws *c* may have pulleys on their lower ends, and be connected by belts, so that when one is turned the other will be turned also, and thus both ends of bed F be raised and lowered at the same time. In lieu of belts they may be provided with gears to be operated by gears upon a long independent shaft properly arranged and combined with the frame of the machine. In this instance the wheel for reducing the leather is provided with spiral knives, but the surface of the wheel or roll may be covered with sand, emery, or other hard substance, the same being applied by any suitable cement or glue. In some cases a fluted cylinder may be employed, and in others card-clothing may be used to cover the surface of the reducing-cylinder. The cylinder may be made of metal and cast hollow, suitable heads being inserted in the ends of the cylinder. The receiving and delivering-rolls may be provided with adjustable spring-bearings, so that a greater or less pressure can be brought to bear upon the material as it passes through them.

In this machine G is the driving-shaft, from which power is communicated to the reducing-cylinder D by means of belt H, and to the shaft I by means of belt J, which runs upon pulley I'. From the cone-pulley K, upon shaft L, a belt runs to the cone-pulley L, upon shaft L', and a belt, M, runs from a pulley on the outer end of shaft L to a pulley on the end of the shaft of the bottom receiving-roll, from which power is communicated to the bottom delivering-roll by means of belt N, as fully indicated in the drawings. It will be seen that the speed of the receiving and delivering-rolls can be regulated by means of the cone-pulleys K and L. The delivering-rolls C C are to be so made or arranged that they will stretch the material somewhat. This can be effected by running them faster than the receiving-rolls, or by making them larger. Cone-pulleys may be fastened to the shafts of the bottom rolls, so that belt N can be adjusted to run the receiving-rolls faster or slower, and thus stretch the material more or less.

The operation is as follows: Motion being communicated to the rolls and reducing-cylinder in any proper manner, the material *e* is passed or fed through under the cylinder D and reduced to the desired thickness. By moving the bed F up or down the material can be varied in thickness.

The value of my invention will be highly appreciated by those engaged in spinning cotton yarn, since by my improvements the leather from which the coverings for the top rolls are made is reduced to a uniform thickness, and which contributes in a great measure to the production of perfect and uniform threads. The leather may be cut up into strips, and the strips fastened together, so that a long piece can be run through the machine readily, and if preferred, the two ends of the piece can be fastened together so that the material can be run through the machine several times in the form of a belt, so that the reduction will be gradual. In the latter case a proper frame should be arranged to support the material above the reducing-cylinder as it returned to pass through between the receiving-rolls, and which frame may be made in any desirable manner. One good way would be to arrange a series of friction-rolls above the reducing-cylinder, the ends of the rolls being sup-

ported in proper bearings upon frame A. The bed F may be recessed or slotted out longitudinally in the centre, and a friction-roll arranged in said recess, to support the leather or material while it is being reduced, and in light work it will be well to use the friction-roll.

Having described and shown one good way in which my invention may be carried out, what I claim as new, and desire to secure by Letters Patent, is—

1. The combination, in a machine for reducing calf-skins, sheep-skins, and lamb-skins to a uniform thickness, of the reducing-cylinder D, receiving and delivering-rolls B B C C, and adjustable bed F, substantially as and for the purposes set forth.

2. A machine for stretching and reducing leather to a uniform thickness, the parts of which are constructed and arranged for joint operation, as and for the purposes herein set forth.

WM. C. JOSLIN.
